UNITED STATES PATENT OFFICE.

WILLIAM FREDERICK McMAHON, OF RIVERSIDE, CALIFORNIA.

NOISELESS ELEVATOR SAFETY STOP.

Application filed December 9, 1924. Serial No. 754,744.

This invention relates to new and useful improvements in elevator or inclined conveyor safety stop mechanism as applied to bucket elevators. While the invention is 5 shown applied to bucket elevators it may obviously be manufactured for any kind of an elevator or inclined conveyor and used to equally good advantage.

This invention includes several important 10 objects among which may be noted first: That of mechanism which makes accidental reversal, or running down of a bucket elevator under load impossible when the electric current to the operating mechanism is shut off. Second: It will increase the efficiency 15 of a bucket elevator or inclined conveyor by preventing the loaded conveyor to reverse itself or carry the load back into the pit or boot. Third: The entire mechanism is 20 noiseless.

With these and other objects in view the invention resides and consists in the construction and novel combination and arrangement of parts hereinafter more fully 25 described and illustrated in the accompanying drawings, and pointed out in the claim hereto appended, it being understood that various changes in the form, proportion, size and minor details of construction within 30 the scope of the claim may be resorted to without departure from the spirit or sacrificing any of the advantages of the invention.

Similar characters of reference denote like 35 or corresponding parts throughout the several figures of the accompanying drawing forming a part of this specification and upon which Figure 1, is a longitudinal side view of a bucket elevator. Figure 2, is an 40 end view of a bucket elevator showing the operating mechanism. Figure 3, is a view of the noiseless elevator safety stop on a larger scale showing the construction of same. Figure 4, is a wiring diagram showing the method of connecting the solenoid 45 with the motor circuit.

Referring in detail to the characters of reference marked upon the drawings.

1 represents buckets, that contain material, 50 and are lifted by means of chain 2 and head sprocket 3, the head sprockets 3 are keyed to shaft 4 which is rotated by spur gear 5 through means of a pinion gear 6 on counter-shaft 7 and motor 9.

55 As this bucket elevator and operating mechanism is of standard construction and

is well known I shall therefore describe only the parts pertaining to my improvement as all other descriptions would be superfluous.

As before stated, this noiseless elevator 60 safety stop is shown applied to bucket elevators. These so called bucket elevators are adapted to convey various kinds of materials in buckets mounted at intervals on one or two strands of chain. They are operated at 65 sufficient speed to discharge their load over the head sprocket by centrifugal force. The head sprocket which operates the strands of chain, is driven by an electric motor. In case of accident or a sudden shutting off of 70 the electric current the loaded elevator will reverse itself and carry its load back into the pit or boot. 8, this is not only annoying and expensive but often dangerous. To prevent this reversal action taking place I have 75 provided a silent ratchet wheel mechanism, the ratchet in this case being keyed to the head sprocket operating mechanism and the pawl is mounted on a structure adjacent to the elevator and is operated by a spring to 80 throw it in engagement with the teeth in the ratchet wheel when the electric current to the motor is shut off, thus preventing the elevator running back, and a solenoid, that is magnetized by the electric current to the 85 motor, to hold the said pawl out of engagement with the teeth in the ratchet wheel when the elevator is lifting the load.

The ratchet wheel 10 which is keyed on the countershaft 7 is a solid cylindrical disc 90 having angular teeth, several in number on its outer edge, and is prevented from running back by pawl 11 which is a metal bar having on one end portion an angular tooth formation of the same shape as the angular 95 teeth on the ratchet wheel and it fulcrums on a pin 12 which is supported by two solid pillow blocks 13 located on each side of the pawl 11. The other end portion of the pawl 11 is an outward disposed lug having a 100 hole in its end to take the bolt 14 that attaches the link bar 15 to same. I have provided this link bar 15, which is a rectangular shaped bar having a bolt hole on each end, to take care of the slight misalignment due 105 to lever motion when the solenoid plunger 16 moves in its constrained longitudinal motion, the solenoid 17 which is of standard construction and the principle of which is well known, when magnetized, pulls the pawl 110 11 out of engagement with the teeth in the ratchet wheel 10. The helical extension

spring 18 serves to pull the pawl 11 into engagement with the teeth of the ratchet wheel thus preventing the ratchet wheel running down when the solenoid 17 is demagnetized. I have provided a hole in the link end portion of the pawl 11 to take one end of the spring and the other end portion of the spring will be fastened to approved construction to a structural member 20 adjacent to the elevator.

The solenoid 17 is magnetized by the same circuit $a-b$ that supply current from the main field lines $a'-b'$ to the motor. I have provided a standard electric controller 19 the principle of which is well known, to start or shut off the current to the motor.

Having now particularly described and ascertained the nature of this invention and in what manner the same is to be performed, I declare that what I claim and desire to secure by Letters Patent is.

In an elevating mechanism, a driven element, an electric motor including a drive shaft, positively acting power transmitting mechanism between said shaft and the driven element whereby the latter is driven from the motor, a ratchet wheel keyed to the motor shaft between the motor and said power transmitting mechanism, a pawl cooperating with the ratchet wheel, a solenoid in circuit with the motor, a core for said solenoid connected with the pawl whereby the latter is held out of engagement with the ratchet while the motor is operating, and means moving the pawl into engagement with the ratchet upon the power to the motor being shut off and the solenoid being de-energized, whereby the elevating mechanism is positively held against backward movement.

WILLIAM FREDERICK McMAHON.
